CIRCUIT INTERRUPTERS

Andrew W. Edwards, East McKeesport, and Kenneth L. Niebauer, Pittsburgh, Pa., assignors to Westinghouse Electric Corporation, East Pittsburgh, Pa., a corporation of Pennsylvania

Application September 28, 1951, Serial No. 248,724

3 Claims. (Cl. 200—150)

Our invention relates generally to circuit interrupters, and it has reference in particular to circuit interrupters of the fluid filled type in which a flow of fluid is utilized in extinguishing an arc drawn during a circuit interruption.

In circuit interrupters it is usually highly important to extinguish the arc as rapidly as possible, so as to complete interruption of the circuit. For this purpose many circuit interrupters have been provided with various means for directing a flow of an arc extinguishing medium into the arc for assisting in extinguishing it. In the main, these interrupters have utilized movable pistons actuated by the moving contact for effecting the flow of an arc extinguishing fluid. This means that the arc will be established before any stream of fluid is directed for extinguishing it. Delay is therefore involved before the arc can be extinguished.

It is therefore an object of our invention to provide for initiating a flow of arc extinguishing fluid in a circuit interrupter before an arc is drawn by the moving contact of the circuit interrupter.

Another object of our invention is to provide for effecting movement of arc extinguishing fluid actuating means in a circuit interrupter before an arc is drawn between the contacts of the interrupter.

Yet another object of our invention is to provide in an interrupter of the fuse type for preventing establishment of the main arc until a flow of arc extinguishing fluid for extinguishing it is initiated.

It is an important object of our invention to provide in an automatic reclosing circuit breaker for permitting the moving contact to have a predetermined amount of travel before separating from the stationary contact, so that a flow of arc extinguishing fluid may be first initiated.

These and other objects of this invention will become more apparent upon consideration of the following detailed description of preferred embodiments thereof, when taken in connection with the attached drawing, in which:

Figure 1 is a substantially longitudinal sectional view of a circuit breaker embodying one form of this invention, with most of the parts within the circuit breaker casing being shown in elevation;

Fig. 2 is an enlarged partial view of the contact structure such as may be used with a circuit breaker similar to that of Fig. 1, in a different embodiment of the invention; and

Fig. 3 is an enlarged view, broken away in part, of a fuse type interrupter embodying the invention in another of its forms.

This invention is disclosed in Fig. 1 as being embodied in a circuit breaker of the type mounted in a metal tank or container 2 having an open top, such as is disclosed in the copending application Serial No. 162,174 of James M. Wallace et al, now Patent No. 2,647,184, issued July 28, 1953. According to such disclosure, a cylindrical liner 4 is provided for the side wall of tank 2, with a liner disk 6 being provided for the bottom of tank 2. The liners 4 and 6 are preferably of an insulating material, such, for example, as fiber or the like. The top of tank

2

2 is adapted to be covered by a cover casting 8, which may be secured to the tank in any desired manner, such, for example, as by bolts 9 (only one of which is shown). Cover casting 8 is adapted to support the circuit breaker mechanism and contacts by means of a plurality of insulating supports 10 (only one shown) secured to integral lugs (not shown) on the under side of the cover casting, and to a casting 14. Other supports 16 of magnetic material are adapted to be connected to the supports 10 to support a plate 18 from casting 14 for mounting a solenoid coil 20 therebetween. Still other insulating supports 22 are adapted to be connected to the supports 16 to support the top cap 24 of an interrupter chamber 26 from plate 18.

The interrupter chamber 26 includes a cylinder 28 of insulating material, such as fiber, having threaded ends, one of which is threaded into top cap 24, and the other end of which is threaded into a bottom cap 30. The bottom cap 30 of the interrupter chamber 26 has a centrally located tapped opening for receiving a contact supporting screw 32 adapted to have a nut 36 on the outer end thereof for securing a conductor 38 thereto. In accordance with the teachings of our invention a normally stationary contact head 34 may be slidably supported on the screw 32, as by a stem 35 which passes axially through the screw 32, a spring 37 disposed about the stem beneath the head 34, and a stop pin 39 which passes through the lower end of the stem for limiting movement of the contact head.

The conductor 38 leads from contact screw 32 to a conductor located in one terminal bushing (not shown) secured to cover casting 8. A movable contact rod 44 has the lower end thereof extending through a central opening in top cap 24 of the interrupting chamber, and is provided with a tubular sheath 46 of insulating material, such as fiber or a molded insulating material at the point where it passes through top cap 24. The lower end of contact rod 44 has a contact head 48 for engagement with the movable contact head 34 on stationary contact screw 32, in the closed circuit position.

Within interrupting chamber 26 there is also provided a fluid directing structure mounted on the lower end of contact rod 44, this structure comprising a top plate 52 having a central opening slidably receiving the lower end of contact rod 44, and a nozzle plate 54 having a central opening somewhat larger than contact head 48, with these two plates being secured together by a plurality of connecting studs 60 which are shouldered to maintain plates 52 and 54 in spaced relation, and are secured in place by screws 62. The fluid directing structure further includes a valve plate 64 located between plates 52 and 54, and being movable between nozzle plate 54 and a stop defined by shoulders on studs 60. The entire fluid directing structure is biased downwardly by a coil compression spring 68 reacting between top plate 52 and the sheath 46 of contact rod 44, with this spring being in a compressed condition in the closed circuit position due to nozzle plate 54 engaging a stop ring 69 held in place between the lower end of cylinder 28 of the interrupting chamber and a shoulder on bottom cap 30. There is also a stop washer 70 secured between contact head 48 and the lower end of the sheath 46 on contact rod 44, to permit locating the plate 52 with a limited amount of resilient lost motion, so as to insure its movement with the rod and yet permit the plate to engage stop 69 without affecting engagement of the contacts 48 and 34.

Bottom cap 30 of the interrupting chamber is provided with a plurality of inlet openings 72 adapted to be controlled by a check valve or ring 74 freely mounted for movement between bottom cap 30 and stop ring 69. The top cap 24 of the interrupting chamber is provided with a hollow chamber 76 having an opening at one side

as at 78, and also communicating with the interior of the interrupting chamber as by outlet openings 80 provided in the inner wall of top cap 24. The outlet openings 80 are adapted to be controlled by a valve ring 82, preferably biased to a position away from openings 80 by a plurality of coil compression springs 84 (only one of which is shown).

The structure of interrupting chamber 26 and its operation is generally similar to that disclosed and claimed in the copending application of J. M. Wallace, Serial No. 542,681, filed June 29, 1944, on Circuit Interrupters, now Patent No. 2,528,197, issued October 41, 1950, and assigned to the same assignee as this invention. Accordingly, reference is hereby made to such copending application for a more detailed description of the construction and operation of this type of interrupting device. In general, as described therein, when contact rod 44 is moved upwardly, an arc will be struck a short time later between the contact tips 34 and 48, and since the interrupting chamber is filled with an arc extinguishing fluid such as oil, being submerged in container 2 which is filled with such fluid up to level L, the arc will decompose the oil and generate gas within the interrupting chamber. This will cause an internal pressure which will seat valve rings 74 and 82 on the inlet and outlet openings, respectively. This internal pressure will also act on contact rod 44 and its sheath 46 in a piston-like manner to accelerate its movement away from fixed contact screw 32. The fluid directing structure starts to move with initial upward movement of contact rod 44 because it is held in engagement with stop washer 70 by spring 68. Accordingly, as contact rod 44 moves upwardly the entire fluid directing structure including nozzle plate 54 will be pulled upwardly with the contact rod, and fluid will be forced from the upper part of the interrupting chamber around the outer edge of plate 52 and through the central opening in nozzle plate 54 to provide a blast of fluid through the contact region in a generally longitudinal direction. In accordance with the teachings of the present invention, the contacts 34 and 48 will not immediately separate to initiate the arc. Instead, after contact rod 44 has moved upwardly an amount equal to the lost motion of stem 35 in screw 32, the moving contact 48 will separate from the contact 34 and an arc will then be drawn. The blast of fluid will already have commenced, and will therefore be available to extinguish the arc drawn between the contact heads, whereupon the pressure within interrupting chamber 26 will decrease and permit valve ring 82 to uncover outlet openings 80 and thus permit escape of gases from the interrupting chamber through outlet openings 80, hollow chamber 76, and openings 78 to be discharged at one side of the top cap 24 for the interrupting chamber. Gases which thus escape from the interrupting chamber are replaced by fresh fluid flowing into the bottom of the interrupting chamber through inlet opening 72, which displaces valve ring 74 upwardly. While the general structure and operation is thus very similar to that disclosed in the above-mentioned copending application of J. M. Wallace, it will be observed that a major difference resides in the method of initiating the flow of arc extinguishing fluid in the interrupting chamber, due to the novel arrangement of the fluid directing structure and the stationary contact.

In order to automatically open the contacts in response to overloads on the circuit, it will be observed that the movable contact rod is connected by a conductor 86 to one terminal of solenoid coil 20 and this, in turn, is connected by a conductor 88 to a terminal bushing 40 which is secured on cover casting 8 by bolts 42. The solenoid coil 20 is thus connected in series with the circuit through contact tips 34 and 48. A solenoid core 90 in the form of a tube is slidably mounted on contact rod 44, being of a magnetic material such as iron. The upper end of solenoid core 90 is slidably received in a

collar 92 secured between supporting plate 18 and the bottom of the solenoid coil 20. The solenoid coil is annular in form and has a central opening receiving a dashpot sleeve 94 of insulating material, such as fiber or a molded insulating material. An actuating tube 96 of a non-magnetic material such as brass or the like, has its lower end secured in the lower end of solenoid core 90 and it extends upwardly through solenoid coil 20, being provided with a collar 97 resting on the top surface of casting 14. A coil compression spring 98 is received within actuating tube 96 and reacts at its lower end against a collar 99 secured in the lower end of tube 96 and at its upper end engages an abutment 99 on contact rod 44, provided by the lower edge of an insulating rod 93 to which the rod 44 is connected.

Casting 14 is also of a hollow construction with the hollow chamber 100 formed within this casting communicating with the upper end of dashpot sleeve 94, and having an opening at one side which may be closed by a plug 102. However, if desired, plug 102 may be removed and the opening from chamber 100 will then be controlled by a piston valve member 104 vertically slidably movable in a counting cylinder 106 mounted in casting 14. The lower end of counting cylinder 106 is closed by a plug 108 having an opening controlled by a ball-check valve 103 to permit fluid to enter the lower end of the cylinder but preventing it from escaping therefrom. Piston valve 104 is provided with a stem 110 at its upper end which has a plurality of annular ratchet flanges 112 formed thereon in spaced relation with the bottom of an extension 113, for engagement by a U-shaped pawl 114 pivotally mounted as at 121 on a lever 116 having a split outer end located at opposite sides of contact rod 44, and resting on collar 97 of actuating sleeve 96. Lever 116 is pivotally mounted on casting 114 at 117, and is normally biased clockwise to keep the outer end in engagement with collar 97, by a coil tension spring 118 secured between lever 116 and a lug integral with casting 14. Pawl 114 is biased in a counterclockwise direction relative to lever 116 by a spring 120, to maintain the pawl in a position for engagement with the bottom of extension 113 and the flanges 112.

The particular construction of casting 14 and parts associated therewith described above is similar to that disclosed and claimed in the copending application of J. M. Wallace et al., Serial No. 719,524, filed December 31, 1946, on Circuit Interrupters, now Patent No. 2,626,329, issued January 20, 1953, and assigned to the same assignee as this invention. Accordingly, for a more complete disclosure of the construction and operation thereof, reference is hereby made to this copending application of J. M. Wallace et al. Generally speaking, the operation of interrupting the circuit, when solenoid coil 20 becomes energized sufficiently to move core 90 upwardly, is that the core first moves upwardly displacing fluid in dashpot sleeve 94 upwardly into casting 14, and if plug 102 is in place the fluid can escape only by way of the relatively small clearance between core 90 and collar 92, so that the upward movement of the core will thus be slowed down by this dashpot action. However, if plug 102 is not in place, the fluid will be freely discharged from chamber 100 in casting 14, and solenoid core 90 will not be restrained in its upward movement, at least on a first circuit interrupting operation in any series of closely successive circuit interrupting operations. Upward movement of core 90, of course, carries actuating sleeve 96 and its collar upwardly, and this moves lever 116 upwardly to carry pawl 114 into engagement with the lower edge of the extension 113 on piston 104 to carry the piston upwardly a predetermined amount. Upward movement of core 90 also will ultimately compress spring 98 sufficiently for the core to cause upward movement of contact rod 44, to thus establish an arc and interrupt the circuit in the manner previously described. After a circuit interruption, core 90 and contact rod 44 are free to descend to

gether to close the circuit, except that, if plug 102 of casting 14 is in place, this descent will be slowed down by the necessity of replacing fluid within the upper part of dashpot sleeve 94 through the relatively small clearance between the core 90 and collar 92. If upon reclosing of the circuit breaker contacts the overload still persists the contacts will immediately be reopened in the same manner except that this time pawl 114 will engage the uppermost flange 112 and counting 104 will be advanced a further amount to a position where it closes the opening from chamber 100, so that the second closing operation will be slowed down by the dashpot action of core 90 in sleeve 94, even though plug 102 is not in place. On a third closely successive circuit opening operation the upward movement of core 90 will be slowed down by the dashpot action of sleeve 94, even though plug 102 is not in place, because piston valve 104 will still be at a position where it closes off the opening from chamber 100 of casting 14. While piston 104 is biased by gravity to reset to its original position, this action is very slow due to the necessity of displacing fluid trapped beneath the piston through the relatively small clearance between the piston and cylinder 106, with the result that piston 104 does not have time to reset where circuit interrupting operations occur in rapid succession.

The upper end 93 of contact rod 44 is connected by a pair of insulating links 124, of fiber or the like, to the common pivot 126 of a pair of links 128 and 130. Link 130 is biased to the left as viewed in Fig. 1 by a coil tension spring 132 connecting link 130 and cover casting 8. However, since link 128, which is of inverted channel form having side flanges, has its other end pivoted on a bracket 136 supported from cover casting 8 as by screws 138, and since link 130 has an integral hook 134 which extends through an opening in the bight portion of link 128, the result is that spring 132 biases link 128 in a clockwise direction, to thus bias contact rod 44 downwardly to exert pressure causing pressure engagement of contact tips 48 and 34.

There is also provided within cover casting 8 a pair of toggle levers 140 and 142 connected by a center pivot 144. Toggle lever 142 has its other end mounted as by a pivot 141 which is secured in a U-shaped lever 143 mounted in cover casting 8 by a pivot 148 and bracket 145, while toggle lever 140 is mounted on a fixed pivot 146 and extends out through an opening in the cover casting beneath a hood portion 147 to form a handle extension 152 having a hook-end 156 in the outer end thereof for manual operation. A coil compression spring 150 engages the bight of lever 143 and the casting 8, thus pushing this lever and center pivot 144 to the left, so that at the position of the parts illustrated, with center pivot 144 located beneath a line extending from fixed pivot 146 to pin 141, the handle extension 152 of lever 140 is maintained in engagement with a stop screw 154 beneath hood 147.

The spring arrangement and mechanism mounted within cover casting 8 is identical with that disclosed in the copending application of H. L. Rawlins et al., Serial No. 719,572, filed December 31, 1946, on Circuit Interrupters, now Patent No. 2,622,167, issued December 16, 1952, and assigned to the same assignee as this invention. Accordingly, for a more complete description of the structure and operation of these parts, reference is hereby made to the Rawlins et al. application. In general, the operation of these parts during a circuit opening operation is such that initial upward movement of contact rod 44 during a circuit opening operation results in levers 128 and 130 approaching each other to thus reduce the force component of spring 132 which biases contact rod 44 downwardly, until the end of spring 132 connected to lever 130 substantially coincides with the pivot mounting of lever 128 on bracket 136. At this time, spring 132 will have substantially no force component in a downward direction, and accordingly, contact rod 44 is not

opposed by spring 132 in its further upward movement. It will be apparent that when the circuit is interrupted, thus freeing contact rod 44 for downward movement, which may or may not be impeded by the dashpot action of solenoid core 90 in dashpot sleeve 94 as previously pointed out, that the parts will move downward initially due to the force of gravity, until the point is reached where links 128 and 130 begin to separate, and thus establish a downward component of spring 132, to accordingly increase the speed at which final engagement of the contacts occurs and, of course, finally establish a contact pressure, as previously pointed out.

Handle extension 152 of toggle lever 140 may, of course, be moved downwardly to move center pivot 144 upwardly overcenter, to thus release spring 150. The lever 143 has a transverse pin 153 which extends beneath the adjacent end of lever 130, so that upward movement of this center pin carries link 130 with it, and consequently, raises contact rod 44 to open the circuit breaker contacts. Such manual opening of the circuit breaker contacts is, of course, accelerated by spring 150 as soon as pivot 144 passes overcenter, and the circuit breaker contacts are maintained open by spring 150. After such a manual operation the circuit breaker may be manually closed by moving handle extension 152 upwardly, and thus permitting contact rod 44 to move downwardly in the manner previously described.

Toggle lever 142 is provided with an extension 158 which overflies extension 113 of insulating material, such as fiber or a molded insulating material, mounted on the upper end of stem 110 of piston 104. The purpose of this is to lock the circuit breaker contacts open after a predetermined number of closely successive circuit interrupting operations have occurred. Thus, as previously pointed out, piston 104 will be advanced a predetermined amount on each circuit opening operation, and if these operations occur in close succession, the piston will eventually be advanced an amount sufficient to cause its extension 113 to engage extension 158 of toggle lever 142, and move pivot 144 overcenter, to thus cause opening of the contacts by spring 150 in the manner previously described, and this spring, of course, will then hold the contacts at an open circuit position.

Instead of utilizing a spring-biased stationary contact such as shown in Fig. 1, the stationary contact may, as shown in Fig. 2, comprise a contact head 34 having a stem 35 extending through the screw 32, and provided with a stop pin similar to the pin 39 of Fig. 1. In place of a spring 34, the stem 35 may have a collar 161 of a permanent magnet material such as one of the well known aluminum nickel alloys. The contact rod 44 may be provided with a contact stud bolt 162 at its end, having a magnetic sleeve 163 of iron or the like disposed thereon. Whenever the contact rod 44 is raised, the stationary contact 34 will follow because of the attraction of the magnet 161 for the sleeve 163, until the stop 39 prevents further movement of contact 34, whereupon the contacts separate. This initial movement of contact 34 permits the nozzle structure to initiate the flow of a stream of arc extinguishing fluid before an arc is drawn between the contacts to provide for more rapid extinction of said arc.

Referring to Fig. 3, the reference numeral 164 denotes generally a circuit interrupter of the fuse type, comprising a tubular housing or container 166 of insulating material such as fiber, glass, or the like, having metal caps 167 and 168 secured to opposite ends. The lower cap 168 is cup-shaped and has an axially projecting internal boss 170 to which one end of a flexible shunt 172 is fastened, and is provided with a flange 173 to which one end of a tension spring 174 may be secured.

The upper cap 167 may comprise a substantially open cylinder and have an internal shoulder 176 for supporting a removable plate 177 having a central opening 178 for receiving the stem of a stationary terminal or con-

tact member 179 which is secured in the opening by means of a collar 180 threaded thereon. A cover 181 may be utilized to close the upper end of the cap 167, being secured to the cap, as by a press fit of a flange 182 about the periphery of the cap.

A movable main arcing contact 183 is normally connected to the stem of the stationary contact member 179 by a fusible link element 184 and a strain element 185, as for example, by solder or the like. The contact 183 has a hexagonal head 186 disposed to be threadably secured to a terminal member 187 at the upper end of the shunt 172. The terminal member 187 has a flange 188 suitably mounted thereon, to which the other end of the tension spring 174 is secured, for applying a predetermined tension to the strain element 185.

In order to direct a flow of arc extinguishing fluid such as a gas-like sulphur hexafluoride, or oil, with which the casing 166 may be substantially filled, a nozzle piston 193 may be secured to the moving arcing contact 183 so as to move therewith. The piston may comprise a cup-shaped member having a central opening 189 for receiving the arcing contact member 183, and a plurality of openings 190 for directing fluid through a reduced annular orifice 192 into the path of an arc between the contacts.

For the purpose of initiating flow of the arc extinguishing fluid before the main arc is drawn between the moving contact 183 and the stationary contact 179, means such as the arc tube 194 may be provided, for providing a circuit connection between the contacts 179 and 183 when the fuse element 184 and strain element 185 blow, for a predetermined movement of contact 183. This tube may comprise adjacent conductive tubular members 195 and 196 disposed axially of the contact 183 and terminal 179, and separated by an annular air gap 197, which is sufficiently short that it will break down while the moving contact 183 is still in contact with the member 196. The member 195 may be secured to the lower side of plate 177 by being mounted on the head 191 of stationary terminal member 179, while the member 196 may be slidably disposed about and in contact with the upper end of the moving contact 183. Means such as the insulating sleeve 198 of fiber or the like may be threadably or otherwise secured to the members 195 and 196 to mechanically connect them and maintain them in predetermined spaced relation.

Accordingly, when the fusible element 184 is melted by a current in excess of the value for which it is designed, the strain element 185, which is of a high strength material, such as a nickel-chromium alloy, and has a relatively high resistance, melts almost immediately, releasing the moving arc contact 183. The contact 183 is thereupon actuated by the spring 174 and the nozzle piston 193 moves therewith to direct a stream of arc extinguishing fluid through the annular orifice 192 about the moving contact 183. The gap 197 flashes over as soon as the fuse element 184 and strain element 185 melt, since it has a breakdown value below that of the voltage impressed thereon when the fuse and strain element melt, and the moving contact 183 remains electrically connected to the stationary terminal 179 by the arc across the gap, until the moving contact reaches the end of the lower section 196 of arc tube 194. A main arc is thereupon drawn between the moving contact 183 and the lower end of the arc tube 194. Since this arc is immediately in the path of the stream of arc extinguishing fluid from the nozzle 193, it is immediately extinguished, and as the arc between the sections 195 and 196 of the arc tube is in series circuit relation therewith, it becomes extinguished also.

It is believed apparent from the foregoing that this invention provides an arrangement for circuit interrupters, whereby a stream of arc extinguishing fluid employed in the interrupter is utilized to extinguish an arc drawn

during interruption of the circuit. An important feature of this construction comprises initiating the flow of arc extinguishing fluid before the main arc is drawn, whereby more rapid extinction of the arc is possible. The invention is equally applicable to circuit breakers and fuses, as shown.

Having described a preferred embodiment of the invention, in accordance with the patent statutes, it is desired that the invention be not limited to the particular constructions described herein, inasmuch as it will be apparent to persons skilled in the art that many changes and modifications may be made in these particular constructions without departing from the broad spirit and scope of the invention. Thus, it is apparent that the invention need not be employed with circuit breakers of the automatic reclosing type, although it has certain novel features of cooperation with this type of circuit breaker, but may be employed in any type of circuit breaker or interrupter where an arc extinguishing fluid is employed. Accordingly, it is desired that the invention be interpreted as broadly as possible and be limited only as required by the prior art.

We claim as our invention:

1. In a circuit interrupter, separable contacts, an arc chamber enclosing said contacts, electroresponsive means operable in response to a predetermined value of current through said contacts to effect separation of said contacts, means movable in said chamber with one of said contacts in a piston-like manner for directing a stream of arc extinguishing fluid in the region of said contacts, and lost motion means for permitting the other one of said contacts to move a predetermined distance in contact with said one contact to permit said stream to be established before said contacts separate.
2. A circuit interrupter comprising, a container for an arc extinguishing fluid, separable contacts disposed in said container, an arc chamber surrounding said contacts, electroresponsive means connected in series with said contacts for moving at least one of said contacts for separating them in response to a predetermined value of current, means for reclosing said contacts following a separation, a movable piston structure disposed in the arc chamber adjacent and movable with said movable one of said contacts for directing a stream of the fluid to extinguish an arc between the contacts, and means including a lost motion mounting for the other of said contacts and means for biasing it to follow said movable one of the contacts to prevent separation of the contacts until the stream is established.
3. In a circuit interrupter, a container for an arc extinguishing fluid, a substantially closed arc chamber in said container, separable contacts disposed in the chamber in said fluid, a movable contact rod for actuating one of said contacts, electroresponsive means including a solenoid connected in series with said contacts and an armature operable in response to a predetermined value of current for actuating said rod to separate said contacts, means biasing said contacts together following a separation, means including an axial stem and spring means for biasing the other of said contacts for predetermined movement with said movable contact, and fluid pump means comprising a piston in the chamber operable immediately upon movement of said movable contact to direct a stream of fluid for extinguishing an arc between said contacts.
